UNITED STATES PATENT OFFICE.

ARTHUR L. PRIMEAU, OF FITCHBURG, MASSACHUSETTS.

PUMP-OPERATING MECHANISM.

1,096,194.

Specification of Letters Patent.

Patented May 12, 1914.

Application filed April 4, 1913. Serial No. 758,911.

To all whom it may concern:

Be it known that I, ARTHUR L. PRIMEAU, a citizen of the United States, residing at Fitchburg, in the county of Worcester and State of Massachusetts, have invented certain new and useful Improvements in Pump-Operating Mechanisms; and I do hereby declare the following to be a full, clear, and exact description of the invention, such as will enable others skilled in the art to which it appertains to make and use the same.

This invention comprehends improvements in pump operating mechanisms and relates more particularly to those of the type especially adapted for use in connection with fluid measuring pumps.

The primary object of the invention is to provide a pump operating mechanism of this nature, which shall be of extremely simple construction, cheap to manufacture, and very accurate and efficient in operation.

Another and more specific object of the invention resides in the provision of operating mechanism including a rack bar, a tubular guide therefor, a pinion extending through the guide and adapted to mesh with said rack bar, and means for rotating the pinion whereby the rack bar may be reciprocated.

The invention also aims to generally improve pump operating mechanisms to render the same more useful, practical, and commercially desirable.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawing, in which,

Figure 1 is a side elevation, the casing and a portion of the operating mechanism being shown in section, Fig. 2 is a front elevation, Fig. 3 is a section taken on the plane of line 3—3 of Fig. 1, and Fig. 4 is a detail view of the rack bar and guide therefor.

Referring in detail to the drawing by numerals, 5 designates a suitable support of any nature formed with the openings 6 and 7. A casing, generally designated 8, is mounted upon the support 5 and contains my improved operating mechanism. This

casing includes a base or bottom plate 9, which is recessed adjacent one end, as indicated at 10, to provide a drip receptacle. Vertical side walls 11, a front wall 12, and a rear wall 13, extend upwardly from the base plate 9, and are secured in position by means of suitable fasteners 14. The front wall is formed in sections and the upper section is curved so as to extend partly over the top of the casing. A downwardly and rearwardly inclined wall 14 extends from the horizontal portion of the front wall to the side wall 11.

It is to be understood that any suitable form of casing may be used in connection with my improved pump operating mechanism, but that the one described is the preferred form.

In carrying out my invention, I provide a tubular guide 15, which is provided upon opposite sides with laterally extending flanges 16, which are enlarged adjacent their outer edges, as indicated at 17. The edges of these flanges abut against the side walls of the casing, as clearly shown in Fig. 3, and are secured thereto by screws 18, which extend through the walls into threaded openings formed in the flanges. A cylindrical rack bar 19 having a flattened side 20 with transversely extending teeth 21 formed thereon, is movable through the guide. The means which I have provided for reciprocating the rack bar include a pinion 22 which projects through an opening 23 formed in the guide and which is adapted to mesh with the teeth formed on the rack bar. The pinion is rigid with a shaft 24 which extends through a bearing 25 formed upon one side of the casing. A crank 26 is secured to the outer end of the shaft 24, which projects a sufficient distance beyond the side of the casing. A handle 27 is secured to the end of the crank and provides means whereby the pinion may be easily rotated.

A fluid measuring pump which is described in detail and claimed in a concurrent application and which includes generally a working cylinder 28, an intake cylinder 29, and a discharge cylinder 30, is secured under the platform 9 by means of rods 31. These rods are rigidly secured to the top of the working cylinder 28, extend through the opening 7 and the base 9 of the casing, and are held against movement by the nuts 32 or other suitable means. The

piston rod 34 is secured to the rack bar 19 by means of a sleeve 35 which is threaded upon the upper extremity of the piston rod and upon the lower extremity of a stud 36, 5 which is threaded into an opening formed in the bottom of the rack bar. The sleeve may be forced tightly against the lower extremity of the rack bar to prevent a movement of the former relative to the latter, 10 and a lock nut 37 may be threaded into engagement with the lower extremity of the sleeve 35 to prevent the piston rod turning therein. By a proper adjustment of the nuts 32 upon the rods 31, the piston rod 15 34 may be brought into accurate alignment with the rack bar 19. An intake pipe 38 leads from a suitable liquid reservoir to the pump and a discharge pipe 39 carries the liquid up through the casing 8 to a discharge nozzle or spout 40, which is positioned over the drip receptacle 10.

A register 41 is secured to the front wall of the casing and is visible through an opening 42 formed therein. This register is for 25 the purpose of recording the amount of liquid which flows through the nozzle 40 and is operated by means of the links 43 and 44, which are connected to each other and to the register and pinion 22, respectively. The link 44 is connected to the pinion by means of a crank pin 45.

In operation, the rack bar 19 is moved by a rotation of the crank 26, first in one direction and then in the reverse direction. A 35 complete rotation of the crank causes a known amount of liquid to be discharged from the pump and flow from the spout 40 and the register 41 records the same.

From the foregoing description taken in 40 connection with the accompanying drawing, it will be seen that I have provided an extremely simple and efficient pump operat-

ing mechanism, which may be very cheaply manufactured and which is especially adapted for use in connection with fluid 45 measuring pumps.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:—

1. In a pump operating mechanism a casing, a tubular guide positioned within said casing, longitudinal flanges formed upon opposite sides of the guide and engaging the interior of the casing, means for rigidly securing the flanges to the walls of the casing whereby the guide is supported and the casing braced, said guide being formed with an opening in the body thereof, a rack bar movable through the guide and means extending through the opening into engagement with the bar to actuate the latter.

2. In combination with a fluid displacement member and a casing, of a rack bar secured to said fluid displacement member, a 70 guide having flanges formed on the sides thereof adapted to engage the walls of the casing, means for securing the flanges thereto, a shaft extending into the casing, a pinion rigid with said shaft, the guide being apertured to permit of the pinion meshing with the rack bar, and a crank rigid with the shaft.

In testimony whereof I affix my signature in presence of two witnesses.

ARTHUR L. PRIMEAU.
